UNITED STATES PATENT OFFICE.

EDWIN FRANK MATTAUSCH, OF ROSALIA, WASHINGTON.

DESIGN FOR A UKULELE.

Application filed April 2, 1923. Serial No. 5,660. Term of patent 3½ years.

To all whom it may concern:

Be it known that I, EDWIN F. MATTAUSCH, a citizen of the United States, and resident of Rosalia, in the county of Whitman and State of Washington, have invented a new, original, and ornamental Design for Ukulele, of which the following is a specification, reference being had to the accompanying drawing, forming a part thereof.

I claim:

An ornamental design for a ukulele, substantially as shown.

EDWIN FRANK MATTAUSCH.
